Primary Examiner — Ania Aman(74) *Attorney, Agent, or Firm* — Ferguson Case Orr Paterson(57) **CLAIM**

The ornamental design for a water heater positioning aid, as shown and described.

DESCRIPTION

FIG. 1 is a top perspective view of the water heater positioning aid.

FIG. 2 is a bottom perspective view of the water heater positioning aid of FIG. 1.

FIG. 3 is a top view of the water heater positioning aid of FIG. 1.

FIG. 4 is a bottom view of the water heater positioning aid of FIG. 1.

FIG. 5 is a right end view of the water heater positioning aid of FIG. 1, the left end view being a mirror image thereof.

FIG. 6 is a front view of the water heater positioning aid of FIG. 1; and,

FIG. 7 is a rear view of the water heater positioning aid of FIG. 1.

1 Claim, 3 Drawing Sheets(56)
